United States Patent Office

Des. 204,331
Patented Apr. 5, 1966

204,331

AIRCRAFT

Augustine W. Robins, Yorktown, Roy V. Harris, Jr., and Harry W. Carlson, Newport News, and Francis E. McLean, Hampton, Va., and Wilbur D. Middleton, Bellevue, Wash., assignors to the United States of America as represented by the National Aeronautics and Space Administration

Filed May 21, 1965, Ser. No. 85,406

Term of patent 14 years

(Cl. D71—1)

(Granted under Title 35, U.S. Code (1952), sec. 266)

FIG. 1 is a top plan view of an aircraft embodying our new design;

FIG. 2 is a side elevational view thereof;

FIG. 3 is a front view thereof;

FIG. 4 is a bottom plan view thereof;

FIG. 5 is a top perspective view thereof; and,

FIG. 6 is a rear view thereof.

The invention described herein may be manufactured and used by or for the Government of the United States of America for governmental purposes without the payment of any royalties thereon or therefor.

We claim:

The ornamental design for an aircraft, as shown and described.
